UNITED STATES PATENT OFFICE.

BENJAMIN HELLER, OF CHICAGO, ILLINOIS.

SPRAY NOZZLE.

Application filed April 5, 1922. Serial No. 549,744.

To all whom it may concern:

Be it known that I, BENJAMIN HELLER, a citizen of the United States, residing at Chicago, in the county of Cook and State of Illinois, have invented new and useful Improvements in Spray Nozzles, of which the following is a specification.

This invention relates to spraying devices of the atomizer type in which the liquid to be sprayed is also placed under pressure and forced thereby from the receptacle to obtain a continuous spraying action irrespective of the direction in which the pump plunger which supplies the air pressure may be moving.

The invention relates more particularly to the spray nozzle of the device, and its object is to provide a nozzle embodying certain novel and improved features of construction, and modes of operation which will be pointed out in the detailed description appearing hereinafter.

In order that the invention may be better understood, reference is had to the accompanying drawing, wherein:

Figure 1 is a front elevation of the nozzle; Fig. 2 is a rear elevation, and Fig. 3 is a central vertical section.

Referring specifically to the drawing, 5 denotes the nozzle body, the same having a base flange 6, and adjacent to the latter a nipple 7 for attachment to the receptacle containing the liquid to be sprayed. The nipple may be screw-threaded as shown, or it may be in the form of a plug if the device is to be attached to a bottle or similar container. One side of the nozzle body is formed with a disk-like enlargement 8 having an outstanding marginal flange 9, and at the center of said enlargement is a nipple 10. The other side of the nozzle body is formed with a nipple 11 which is screw-threaded externally to receive and hold a nozzle cap 12.

In the nozzle body 5 is imbedded a liquid delivery tube 13 which has one end passing through the nipple 7 to extend into the bottle or other receptacle containing the liquid to be sprayed. The other end of the tube 13 extends laterally and passes through the nipple 11, and from which latter it extends into the cap 12 and terminates to the rear of outlet orifice 14 thereof. The nozzle body will be a die-casting, the tube 13 being laid in the mold while the nozzle body is being cast.

The nozzle body 5 is also provided with a transverse air-passageway 15 which opens at one end through the nipple 11 to discharge into the cap 12 and alongside the protruding discharge end of the tube 13 in the direction of the orifice 14. The other end of the passageway 15 opens through the nipple 10, and is here enlarged to receive a tight-fitting brass bushing 16. The nozzle body also contains a longitudinal air-passageway 17 opening at one end through the nipple 7, and having its other end in communication with the passageway 15. At the junction of the passageways 15 and 17, the former is enlarged sufficiently to form a chamber 18 containing a ball check valve 19. The inner end of the bushing 16 has a beveled seat 20 for the valve 19. The wall of the chamber 18 also has a rib 21 to prevent the valve 19 from taking a position closing the passageways 15 and 17.

If the device is to be operated by an air-pump consisting of a cylinder and a reciprocating plunger working in the latter, the pump cylinder will be attached to the flange 9. If the device is to be operated by a rubber bulb, the latter can be attached to the nipple 10. In either case air is forced through the bushing 16 to unseat the valve 19, and this air is discharged through the passageway 15 past the outlet end of the tube 13, so that the suction created at said end draws the liquid through the tube to discharge into the cap 12 from which latter it escapes through the orifice 14 in the form of a fine spray, the action being similar to an ordinary atomizer. Some of the air also escapes through the passageway 17 into the receptacle containing the liquid to be sprayed, and the pressure thus produced on the surface of the liquid tends to force the liquid out of the receptacle through the tube 13, and in this way the spraying action is made continuous, and there is no interruption during the return or suction strokes of the pump. Referring to Fig. 3, it will be noted that the interior of the cap 12 tapers toward the orifice 14, and as the discharge end of the tube 13 is centrally located in the cap in alignment with the orifice 14, the annular space around said tube end may be widened or contracted by advancing or backing the cap, which can be readily done as it is screwed on the nipple 11, and in this way the volume of air passing the outlet end of the tube can be increased or de-

creased to enable the operator to control the volume of fluid to be sprayed and the fineness of the spray.

By employing the die-casting process in the manufacture of the device, the nozzle bodies from each set of patterns in the various sizes made, will be absolutely accurate and uniform. The cap 12 can be cast or molded from some acid-resisting metal or other material. The device is simple and compact in construction, and its use is not limited to any special design of liquid container or receptacle, it being readily applicable to any ordinary can, bottle or other container, and capable of use in connection with any kind of spraying or atomizing apparatus. The preferred embodiment of the invention has been disclosed, but it will be understood that various changes and modifications may be made without a departure from the spirit and scope of the invention as claimed hereinafter.

I claim:

1. A spray-nozzle comprising a body having means at one end for attachment to a liquid receptacle, and provided at one side with a nipple and on the opposite side with means for attachment of a pump, said body also having an internal transverse air passageway the outlet end of which opens through the nipple and its inlet end opening through the side having the pump-attaching means, and also provided with a second air-passageway leading from the first-mentioned passageway and having its outlet end located at the end of the body having the receptacle-attaching means, a check valve at the junction of the passageways, the inlet end of the first-mentioned passageway having a seat to receive said valve, said passageway having an enlargement forming a chamber in which the check valve is located, a rib formed in said enlargement at the junction of said passageways to limit movement of said valve in the direction of said second passageway and the

outlet of said first mentioned passageway from said enlargement, to prevent closing of the same, a liquid delivery tube passing through the body and having its inlet end 50 extending from the aforesaid end thereof, and its outlet end projecting from the nipple, and a cap mounted on said nipple over the projecting outlet end of the tube, said cap having a discharge orifice in line with 55 the outlet end of the tube.

2. A spray-nozzle comprising a molded body having means at one end for attachment to a liquid receptacle, and provided at one side with a nipple, said body having a 60 transverse air passageway extending through said nipple having its inlet in the opposite side of said body; a circumferential pump retaining flange surrounding said inlet, the body having an internal longitudinally disposed passageway leading into said transverse passageway and having its outlet located at the end of the body having the receptacle attaching means; said transverse passageway having an enlargement into the 70 outlet end of which said longitudinal passageway leads and a valve seat in the inlet end of said enlargement; a valve in said enlargement adapted for location in said seat; means positioned in said enlargement 75 remote from said valve seat and in the path of said valve to prevent the same from moving to close said longitudinal passageway inlet and the outlet end of said enlargement, and a liquid delivery tube passing through said body molded bodily therein, said tube having its inlet end extending from the aforesaid end of said body, and its outlet end projecting from said nipple; and a cap mounted on said nipple over the projecting 80 outlet end of said tube, said cap having a discharge orifice substantially concentric with the outlet of said tube.

In testimony whereof I affix my signature.

BENJAMIN HELLER.
